UNITED STATES PATENT OFFICE.

GEORGE C. RUECKERT, OF PROVIDENCE, RHODE ISLAND, ASSIGNOR OF
ONE-HALF TO BERTRAM LENZEN, OF SAME PLACE.

DESIGN FOR A BUTTON-HOLDER.

SPECIFICATION forming part of Design No. 32,430, dated April 3, 1900.

Application filed February 26, 1900. Serial No. 6,645. Term of patent 7 years.

To all whom it may concern:

Be it known that I, GEORGE C. RUECKERT, a citizen of the United States, residing at Providence, in the county of Providence and State of Rhode Island, have invented and produced a new and original Design for Button-Holders, of which the following is a specification, reference being had to the accompanying drawings, forming a part thereof.

Figure 1 is a plan view of a button-holder, showing my new design. Fig. 2 is a sectional view taken on line 2 2 of Fig. 1.

As shown in the drawings, the leading or material feature of my design consists of a series of V-shaped slots *a a a a* and circular

perforations or openings *b b b b*, disposed and arranged as shown in Fig. 1, the slots each terminating in the said perforations. The V-points are outwardly curved, as shown in Fig. 2.

I claim—

The design for a button-holder, as herein shown and described.

In testimony whereof I have signed my name to this specification in the presence of 25 two subscribing witnesses.

GEORGE C. RUECKERT.
